Atty.

UNITED STATES PATENT OFFICE.

INNOCENTE SORDI, OF MILAN, ITALY.

ARRANGEMENT FOR THE HEATING OF ROOMS BY MEANS OF ELECTRIC THERMOGEN.

1,318,237.

Specification of Letters Patent.

Patented Oct. 7, 1919.

Application filed August 28, 1918. Serial No. 251,754.

To all whom it may concern:

Be it known that I, INNOCENTE SORDI, a subject of the King of Italy, and resident of Milan, Italy, have invented certain new and useful Improvements in Arrangement for the Heating of Rooms by Means of Electric Thermogen, of which the following is a specification.

This invention relates to improvements in liquid heaters and particularly to electrically heated means for heating liquids.

One of the objects of my invention is to provide improved electrically heated means through which water or the like may pass, and this means may be inserted in the piping of a radiator heating system or it may be connected with the water pipes of a building, so that the water passing through the piping or pipes will be heated.

20 A further object of the invention is to provide a liquid heating means in which the liquid will be pre-heated while traveling in one direction through the device and will be additionally heated while traveling in the opposite direction through the apparatus.

A still further object is to furnish a liquid heating apparatus made up of sections or units, so that the apparatus may be built up to the size necessary for purpose desired.

30 With the foregoing objects outlined and with other objects in view, the invention consists in the novel features hereinafter described in detail, illustrated in the accompanying drawing, and more particularly 35 pointed out in the appended claims.

Referring to the drawing, A represents the sections of the heater, each of which consists of a casing 1 in which is arranged two concentric pipes 2 and 3. These pipes 40 2 and 3 are spaced apart to provide an annular chamber having closed ends, and heating means, such as an electric resistance 5, is placed in this chamber. The electric resistance is insulated from the pipes by means 45 of insulating packings 4, and these packings, while preventing electric current passing to the pipes, permit the heat of the resistance to reach and heat said pipes.

The space formed between the casing 1 50 and the pipe 2 of one section A is connected

by a pipe 6 to the pipe 3 of the succeeding section, so that liquid passing through the pipe 3 of the first section will have to pass between the pipe 2 and the casing 1 of that section before it reaches the pipe 3 of the 55 next section.

The pipe 3 of the first section A of the apparatus has an inlet continuation s, and the casing 1 of the last section of the apparatus has an outlet continuation t. It will 60 be noted that all of the pipes 6, s and t are connected to the sections at one end of the casing 1 and it is obvious that the purpose of this is to cause the liquid to travel in a zig-zag path through the apparatus, so that 65 the water will first travel through a heated pipe and then along the exterior of another heated pipe. In this manner the full capacity of the heating means is utilized.

The ends m and n of the resistances are 70 connected to the electric line wires.

The ends s and t of the apparatus may be connected to sections of the piping of a building water system, so that water drawn off by the cocks or faucets may be quickly 75 heated, or these ends may be connected to sections of the piping of a water heating system, whereby the apparatus may be utilized for heating the water passing to the radiators.

The apparatus may also be used in a water heating system instead of the ordinary radiators.

It is obvious that the water may also be circulated in a reverse direction through the 85 apparatus.

What I claim and desire to secure by Letters Patent is:—

1. A liquid heater comprising an elongated casing consisting of an imperforate 90 tubular body having an aperture arranged in close proximity to one of its extremities and provided at one end with an imperforate head and at its other end with a head having an aperture, a double walled conduit 95 extending into said casing from the apertured head of the casing and having an open end arranged in close proximity to the imperforate head of said casing, a pipe secured to the body and passing through the 100

aperture in the body, another pipe passing through the aperture of the apertured head and integral with the inner wall of said conduit, and an electric resistance located between the walls of said conduit for heating liquid passing through and around said conduit.

2. A group of liquid heating elements as defined in claim 1, in which the pipe con-

nected to the body of one casing extends to 10 and integral with the pipe forming the inner wall of the conduit in an adjacent casing.

In testimony whereof I affix my signature, in presence of two witnesses.

INNOCENTE SORDI.

Witnesses:

GIAN GIACOMO GUARNIERI,

IVAN LAVRETSKY.
